MINING PLANER

Julius Herrmann, Wethmar, near Lunen, Westphalia, Germany, assignor to Gewerkschaft Eisenhuette Westfalia, Lunen, Germany, a German corporation

Application June 15, 1953, Serial No. 361,753

Claims priority, application France July 8, 1947

5 Claims. (Cl. 262—8)

This invention relates to an improved mining planer and is a continuation-in-part of U. S. patent application Serial No. 29,432, filed May 27, 1948, now abandoned.

A certain type mining planer comprises a planer cutting head which is movable in either direction alongside a longitudinally extending conveyor. The planer head may be provided with cutters for cutting in each direction of movement and is drawn back and forth along the leading portion of the conveyor.

The mining planer is particularly well adapted for a type of mining known as long-wall mining and may be used for efficiently removing coal by the long-wall method and especially from narrow seams.

In operation the planer conveyor is positioned along the mine face of a long-wall panel and rests on the mine floor. The conveyor is urged toward the mine face and the planer cutting head is drawn back and forth along the conveyor. The planer thereby cuts and turns or plows cut material in a substantially continuous manner into the conveyor which, in turn, continuously transports the material for removal. The planer head is rigidly mounted on a base member and is drawn back and forth along the conveyor by means of relatively flexible traction elements, such as chains or cables attached to the side of the base member and actuated by suitable drive means. In each direction of travel, one of the cutting edges is in cutting position, while the other is dragged along the mine face. This entails a waste of power and often causes operational difficulties.

It was not possible to uniformly and reliably obtain a clean cut on the mine shaft floor. Very often, as, for example, in coal mining, the planer would leave coal undetached from the shaft floor. This was particularly true with respect to hard spots, over which the planer head would ride rather than remove the same.

In addition, with the rigid head construction, the optimum cutting angle could not be maintained on both cutting edges.

One object of this invention is to overcome the above-mentioned difficulties and provide a planer head in which the non-cutting edge in any particular direction of travel will not drag along the mine face and interfere in operation, and in which an optimum cutting angle may be maintained for both cutting edges when in operation. These, and still further objects will become apparent from the following description read in conjunction with the drawings, in which

Fig. 1 shows a side elevation partially in section of a mining planer in accordance with the invention;

Fig. 2 shows a top elevation of the planer shown in Fig. 1;

Fig. 3 shows a perspective view of the planer head and base member of Fig. 1 showing the relationship of the parts;

Fig. 4 shows a side elevation partially in section of a different embodiment of a planer;

Fig. 5 shows a top elevation of the planer shown in Fig. 4;

2

Fig. 6 shows a perspective view of the planer head shown in Fig. 4;

Fig. 7 shows a detailed view of a different embodiment of a pivot joint in accordance with the invention; and

Fig. 8 shows a diagrammatic representation of a complete planer unit in operation.

The planer in accordance with the invention is provided with a planing head having two cutting edges arranged to cut in substantially opposite directions. A base member is provided which is adapted to be drawn back and forth along the longitudinally extending conveyor in either direction and is preferably guided along the forward portion of the conveyor, as, for example, on a guide rail. The planer head is pivotally mounted on the base member for pivoting within a limited arc of pivot, so that one of the cutting edges is tilted into non-cutting position and the other into cutting position when the planer head is moved in cutting contact and in the cutting direction for the last-mentioned edge. Thus, in one direction of travel of the planer head one of the cutting edges will be pivoted into the optimum cutting position and the other will be tilted out of the way so that it will not drag along the mine face and impede the operation. When the direction of travel of the planer head is reversed, the same will pivot on the base member so that the situation is exactly reversed. The term "cutting edges" is used to generically define the cutting portion of the planer head. These cutting edges, for example, may be collectively defined by a multiple number of individual knives or chisels.

Within the preferred embodiment of the invention the planer head is so pivotally mounted on the base member within a limited arc of pivot, that one of the cutting edges will be tilted upward into a non-cutting position and the other tilted downward into a cutting position when the planer head is moved in cutting contact and in cutting direction for the last-mentioned edge. This, for example, may be obtained by having the pivot axis inclined in a forward direction to thereby effectuate downward self-adjustment of the edge which is in cutting position. In this manner a substantially clean and even cut with respect to the shaft floor is assured.

Though the invention is described in the following as preferably applied to the mining of coal, it may be used for the mining of other types of minerals.

45 The conveyor comprises multiple, preferably flexibly connected sections A, each having two lateral sections 1 and 2, and a conveyor bottom 3 substantially forming a trough. Parallel, spaced-apart flights of scraper bars 4 are continuously drawn along the upper surface of the bottom portions 3 and returned along the under surfaces of the latter by means of endless chains 5 and 6 moved by a suitable drive (not shown). As the flights of scrapers are drawn along the bottom portion 3, coal is pushed along and conveyed.

50 A guide member in the form of a guide track 9 extends longitudinally along the leading edge of the conveyor and is attached to the conveyor.

An apron 8 forms an inclined surface over which coal cut by the planer head is guided into the conveyor. Such an apron or similar inclined guide surface is not, however, essential to operation and the shape of the planer alone may serve to guide the coal cut into the conveyor.

A base member 7 is positioned to slide back and forth along the leading edge of the conveyor in the guide track 9. As shown in Figs. 1, 2 and 3, the base member 7 has the guide beam 10 connected thereto, which is guided in the track 9. A flexible traction element such as a cable, rope or chain is attached to both sides of the base member for pulling the base member in one or the other direction.

65 As shown in Figs. 1, 2, and 3, the flexible traction element is in the form of a cable which is attached to the end of the guide beam 10. The flexible traction element may

be actuated by any suitable reversible drive means (not shown) and may be endless and return in the hollow portion of the apron 8.

The planer head 12 is pivotally mounted on the base member by means of a pivot post 13 extending upwardly from the base member through the pivot aperture 14 defined in the planer head 12. The axis of pivot is the axis of the pivot post 13.

The second post 16 is connected to the base member and extends into a slot 15 defined in the planer head. The movement of the slot relative to the post 16 defines the limited arc of pivot of the planer head. The planer head has two opposed vertical edges 17 and 18 for cutting in opposite directions of travel.

The planer head may be pivotally connected to the base member in any other desired manner and thus, for example, as shown in Fig. 7, a post or pin 13 may be connected to the head, which pin extends into an aperture 14 defined in the base member. In the same manner, any known or conventional pivot connection of suitable strength may be used.

The limiting of the arc of pivot of the planer head on the base member need not be effected by separate stop means such as the pin 16 and slot 15, but may be effected by dimensioning of the planer head and base member so that the planer head will contact the base member after the desired arc of pivot thus limiting the same. In the same manner the arc of pivot may be limited by any conventional stop means or by any suitable dimensioning of the planer head to strike a non-pivotal portion of the planer at the two extremities of the act of pivot, thus limiting it.

In operation of the mining planer it is often difficult to detach the mineral such as coal from the mine floor. This is particularly true when using a planer in which the planer head is rigidly attached to the base member. In order to overcome this difficulty in accordance with a preferred embodiment of the applicant's invention, the axis of pivot of the planer head is inclined somewhat in a forward direction. This construction allows the planer head, when pivoting within the limited arc of pivoting, to tilt one of the cutting edges upwardly into a non-cutting position and the other downwardly into a cutting position when moving the planer head in cutting contact in a cutting direction for the last-mentioned edge. This allows downward self-adjustment of the edge which is in cutting position, so that it glides sharply over the mine floor and may even scratch the same a little. This overcomes the prior-encountered difficulty of detaching the mineral such as coal from the mine floor.

As shown in the drawings, the axis of the pivot post which defines the axis of pivot between the pivot head and base member is positioned in a vertical plane and is inclined forward slightly, so that the same almost forms a right angle with the inclined surface 8.

In the embodiment shown in Figs. 1, 2, and 3, the base member has a guide beam 10, which is guided in track 9. The guide beam is slightly tapered at its ends, which allows a slight horizontal tilting thereof in the guide track 9.

An under plate or "sword" 20 attached to the base member extends beneath the conveyor and travels with the base member. The under plate or sword extends beneath the conveyor and the weight of the conveyor rests thereon. This under plate will maintain the vertical positioning of the planer head and base member and prevent the same from rising or creeping upwardly during operation or lifting from the mine floor during operation. The under plate or sword may additionally serve to detach coal from the shaft floor and to scrape the same clean, and for this function may be provided with an edge on each side.

In the embodiments shown in Figs. 4, 5 and 6, the two vertical cutting edges are defined by a multiple

number of vertically positioned cutting chisels 21, which may be positioned in a step-like manner.

The base member in this embodiment defines a tubular channel 22 therethrough. A tubular guide rail 23 is positioned along the forward portion of the conveyor. In operation, the base member is positioned on the guide rail so that the guide rail extends through the tubular channel and the base member is positively guided along the guide rail.

10 The planer head with the cutting edges defined by the cutting chisels is pivotally mounted upon the base member for tilting within a limited arc of pivot in the same manner as in the embodiment shown in Fig. 1. The axis of pivot is in a vertical plane and preferably inclined in a forward direction.

The base member and/or the forward portion of the conveyor and/or the guide member on which the base member is guided along the conveyor define an inclined path into the conveyor adjacent the planer head, so that 20 the mineral cut by the cutting edges will be guided into the conveyor.

In operation, the conveyor is positioned longitudinally along a mineral mine face such as the solid coal face 26 (Fig. 8) in a long-wall panel. Removable mine 25 props 24 are positioned behind the conveyor. The conveyor is urged forward, as, for example, by multiple pneumatic jacks 25 positioned along the conveyor. The flexible traction element 11, such as a chain or cable, is pulled by means of a suitable drive means 27. This 30 pulls the base member and thus the planer head. The planer head is drawn along the entire mine face along the conveyor in first one direction and then the opposite direction. As the planer head is pulled in each direction, the pressure and force of the cutting edges on the mine face will automatically cause the head to tilt into the correct position. The non-cutting edge, i. e., the following edge in the direction of travel, is automatically tilted out of the way, and the cutting edge, i. e., the leading edge in the direction of travel, is tilted 35 into the optimum cutting position. If the axis of pivot is inclined forward slightly, the cutting edge, i. e., the leading edge in the direction of travel, will be tilted downwardly and efficiently remove the coal from the mine floor while the non-cutting edge, i. e., the following edge in the direction of travel, will be tilted upwardly out of the way. As the base member of the planer head is drawn back and forth along the mine face, the planer head with its cutting edges will strip or plane layers of coal, as from the solid coal face in the long-wall panel. The coal so planed off will then 40 be turned or plowed into the conveyor which automatically, continuously removes the same. The height of the planer should normally be $1\frac{1}{2}$ to $2\frac{1}{2}$ of the seam thickness. The top coal will break down, due to its own weight, and drop into the conveyor after being undercut. The height of the planer head and the cutting edges may be varied by adding or removing extension 45 pieces.

The sections A of the conveyor are connected to each other so as to allow a limited flexing at the connections in a vertical and horizontal direction. The entire conveyor will thus be somewhat flexible and will to a certain extent follow the contour of the mine floor and the mine face.

60 The pneumatic jacks 25 are maintained under a continuous pneumatic pressure and thus continuously force the conveyor toward the mine face. This maintains the planer head in cutting contact with the mine face and automatically shifts the conveyor forward toward the mine face as the planer head is drawn back and forth and coal is planed off from the face and removed by the conveyor. The planer will therefore continuously move forward and plane away the mine face.

A suitable working space is maintained about the conveyor by means of the mine props 24. Generally, as the

conveyor advances into the mine face removing the same, the back row of jacks are removed and shifted to the forward position. The mine ceiling which is supported by this back row of jacks then begins to collapse, and as the machine continuously moves forward into the mine face, the shifting or robbing of the jacks causes the mine area back of the conveyor to collapse and only a working space as defined by the jacks is continuously maintained.

The planer unit is a continuous mining machine and will continuously mine coal from a solid face, plow the coal into the conveyor, convey the coal to any suitable discharge, as, for example, additional conveyors 28, such as chain or belt conveyors, wherefrom the coal is deposited into cars or the like.

I claim:

1. In a mining planer having a planer cutter movable back and forth along the forward portion of a longitudinally extending conveyor, the improvement which comprises guide means positioned along the forward portion of said conveyor, a base member movably positioned for back and forth motion along said guide means in guided relation thereto, a planer head, having two planing cutting edges thereon arranged to cut in substantially opposite directions, pivotally mounted on said base member about an axis of pivot lying in a substantially vertical plane and inclined forwardly in the direction transverse of the path of the planer head to permit pivoting of the planer head within a limited arc of pivot to tilt one of said cutting edges upwardly and into a non-cutting position, and the other edge downwardly and into a cutting position when moving the planer head in cutting contact

in the direction of said last-mentioned edge, and means for moving said base member back and forth along said conveyor.

2. Improvement according to claim 1, in which said planer head is pivotally mounted about a pivot post connected to said base member.

3. Improvement according to claim 2, in which said pivot post lies in a substantially vertical plane and is inclined forwardly in a direction transverse to the path of the planer head to permit the downward self-adjustment of the edge, which is in cutting position.

4. Improvement according to claim 1, in which said planer head is connected to a pivot extending into a pivot aperture defining said base member.

5. Improvement according to claim 4, in which said pivot post lies in a substantially vertical plane and is inclined forwardly in a direction transverse to the path of the planer head to permit downward self-adjustment of the edge, which is in cutting position.
